Primary Examiner — Lilyana Bekic(74) *Attorney, Agent, or Firm* — Chung-Ming Shih; HDLS IPR Services(57) **CLAIM**

The ornamental design for a nasal mask, as shown and described.

DESCRIPTION

FIG. 1 is a perspective view of a nasal mask showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a second perspective view showing the nasal mask. The broken lines in the drawings illustrate portions of the nasal mask that form part of the claimed design.
